PEN GUARD

Kenneth W. McPherson, Palmyra, N. Y.

Application December 1, 1937, Serial No. 177,623

5 Claims. (Cl. 120—114)

This invention relates to improvements in writing pens, and its fundamental purpose is to effect easier and more economical writing, the ink being conserved considerably.

5 It is common knowledge with persons who have given the matter any degree of attention and study, that as much if not more ink is lost by evaporation than is used in writing. Contrary to what might be regarded as popular belief, the protecting cap of a fountain pen does not afford the absolute protection against evaporation that one might expect.

10 It is not the object of the invention to prevent ink evaporation from a fountain pen when the screw cap is in place because this is an inherent effect which is not readily overcome. But when a fountain pen is laid down with the nib exposed, it is possible to prevent a large percentage of evaporation and it is protection against this evaporation that is more particularly afforded by the invention.

15 Another prolific source of ink loss, other than that occasioned by actual writing is the periodic flooding and spurting of ink at the point, particularly in fountain pens. This troublesome effect is usually accompanied by an ink spot on the paper, and the ink spot is enabled to fall from the point because there is nothing to stop it.

20 With these difficulties in mind, attention is directed to the invention, the objects of which are as follow:

25 First, to provide a guard for the nib or point of writing pens for the purposes of conserving the ink supply by retarding evaporation, retaining the ink in a wet state extremely near the writing tip, preventing concentration of the ink and hence dark writing at the beginning of use of the pen, and preventing both flooding and 30 spurting to a considerable degree.

Second, to provide a guard for the nibs of pens, forming a small pocket in the very tip of the guard to contain the ink, and facilitate free starting and proper flow of ink.

35 Third, to provide a guard for fountain pens to prevent or at least lessen the excessive gathering of ink at the end of the nib, thus effecting more even-flow writing.

40 Other objects and advantages will appear in the following specification, reference being had to the accompanying drawing, in which:

45 Figure 1 is a plan view of a portion of a fountain pen illustrating one of several types of guards attached to the nib.

Figure 2 is a detail longitudinal section taken on the line 2—2 of Fig. 1.

Figure 3 is a partial plan view of a fountain pen illustrating the application of another type of guard to the nib.

Figure 4 is a plan view of a portion of a fountain pen illustrating the application of a third type of guard to the nib.

Figure 5 is a longitudinal section taken on the line 5—5 of Fig. 4.

Figure 6 is a plan view of a portion of a fountain pen illustrating the application of a fourth type of guard to the nib.

Figure 7 is a longitudinal section taken on the line 7—7 of Fig. 6.

Figure 8 is a plan view of a fifth type of pen guard.

Figure 9 is a partially elevational and sectional view illustrating the application of the type of guard in Fig. 4 to a fountain pen and showing a knurling.

Figure 10 is a magnified cross-section taken on the line 10—10 of Fig. 9.

A desirable substance out of which to make the guards is Celluloid or such other moldable plastic as cellulose nitrate or acetate, or some similar compound or composition. This material has a degree of yieldability so that it can be slipped into place, and has the added advantage of being glossy, so that it can be used in conjunction with fountain pen nibs, which are not made of gold. The guard may be constructed of rubber or metal, in whole or in part.

Reference is made to the drawing. In each instance the guard is designated 3. It is slipped onto the nib in the manner illustrated. For this purpose the point 4 of the guard either has a hole, as in Figs. 4, 5, 6, and 7, or is split as in Figs. 1, 2 and 8 to contain the point of the nib.

The first form of the invention is illustrated in Fig. 1. Here the guard 3 is applied to the nib 13 of the fountain pen 14. In this instance the guard comprises a relatively extensive nether wall 15 (Fig. 2) which covers most of the feed bar 16. This nether wall merges into side portions 17 (Fig. 1) which touch the sides of the nib 13 and close in upon the convex surface of the latter to a slight extent, as indicated at 18. These side portions are connected by a bridge 19 which in this case completely closes the nib perforation 20, the customary slit 21 being left unobstructed.

In order that the slit 21 may not be restricted in any sense, the guard end 4 (Fig. 1) is made

open at 22. The lateral portions of the nib are free to flex, but the point end 4 being open at 22 does not obstruct this flexing in the least.

It will be noticed in Figs. 1 and 2 that the 5 guard provides a virtually complete closure for the perforation in the nib. The purpose of this closure is to prevent to a high degree evaporation of the ink.

Attention is next directed to the second modification in Fig. 3. Here the guard 3 comprises an almost complete enclosure for the nib of the fountain pen 14. Provision is made of a collar 23, the purpose of which is to diminish the possibility of the ink running out on the outside of 15 the guard should ink well out from inside of the pen. In the event of making this guard 3 of Celluloid, a desirable possibility as presently appears, the margins of its open, nether side would reach to the places designated 23a. Here 20 the guard is on the order of a cap, the natural resilience of the Celluloid enabling its being snapped onto the convex back of the nib and around to the concave side where the edges of its split 23b meet as shown.

25 It is common knowledge that fountain pens have irregular ways of acting, some holding the ink back and others allowing it to temporarily well out. The collar 23 tends to prevent drops of ink from flowing over onto the guard and should there be any welling out the right side of the collar, the latter will afford enough of an obstruction to hold the ink until the user has had time to remove it with a blotter.

Figure 4 illustrates the third type of guard. 30 The general configuration of this guard is the same as that in Fig. 1, the main exception being that a reservoir wall 24 is employed instead of leaving the guard open as at 22 in Fig. 1. A bridging wall 25 is again employed as the closure for the customary nib perforation, and a further 35 distinction resides in making the nether wall 26 (Fig. 5) thicker than in the other forms. The purpose and advantage of the thickened wall is insurance against relaxing of the rubber and a 40 consequent loosening of the guard from the feed bar.

Figure 6 illustrates the fourth type of the guard 3 wherein the structure 27 on the convex side of the nib resembles a frame. The guard 45 has a nether wall 28 (Fig. 7) as in Figs. 2 and 5. The socalled frame structure (Fig. 6) includes a holding band 29 and instead of there being a cross bridge to cover the nib perforation, there is a mid extension 30 which reaches in from the 50 point end 4. Inasmuch as the guard 3 is made of more or less fragile material in all cases, it is desirable and necessary to make the extension 30 sufficiently heavy (Fig. 7) to prevent its riding up from the desired covering position over the 55 perforation. The extra thickness indicated makes the mid extension 30 sufficiently stiff to serve the purpose.

Figure 8 is an illustration of a type of guard as in Fig. 1, but omitting the bridge 19 there 60 shown. The side portions 17a close in at 18a as before, but the absence of a bridge at 31 is to be noted. This is the first one of all of the forms in which the nib perforation 20a is left 65 open, showing that only types of guards which close this perforation are not necessarily adhered to.

Figures 9 and 10 are primarily intended to 70 illustrate means other than thickening of the rubber (Fig. 5) for preventing the guard from slipping off of the nib. It is obviously necessary

to have the guard stay in place, yet a very close fit upon the nib is not so desirable. The remedy according to Figs. 9 and 10, is a knurling 38. This knurling or some equivalent roughening is produced on the inner surface of the ring or 75 wall 39.

In Fig. 9 the guard 3 is fitted upon the nib 40 and feed bar 41 of the fountain pen 42.

It is desired to state at this point that the confinement of the knurling to the showing in 10 Figs. 9 and 10 does not mean that the other types of guards are not subject to similar treatment. Any one or all of the previous types are intended to be supplemented with a roughening of some kind to contact the pen parts and thus 15 facilitate movement of the ink and insure the retention of the guard especially in cases where there is a little inherent looseness due to uncontrollable differences in nib sizes.

By manipulating the guard off and on the size 20 of the nib opening can be minutely regulated, and it can be fixed in the place desired. In general the device is moved outward to increase ink flow and to facilitate air-intake, but it may in some cases be to increase the space for ink 25 around the feed bar. When the guard is way on, the exposure of ink to the air is at a minimum.

This reservation also applies to the employment of a finger-piece 39a, shown in Figs. 2 30 and 9, but capable of combination with any one of the other modifications. This so-called finger-piece provides a place behind which one can catch his finger nail for facilitating pulling the 35 guard off.

It will be understood from the foregoing description that there is no hard and fast rule about how to make the pen guard or what material to construct it of. The various modifications are provided to serve different kinds of pen. But in all instances the following advantages 40 result from the use of a guard of one type or another:

First, the evaporation of ink is lessened because less of its surface in the concave of the nib is exposed to the air than in ordinary dip and fountain pens.

Second, because of the fact that the working quantity of ink, namely, that amount which is held in the point of the nib, is protected from the air to such a large degree there is less drying and consequently quicker and better starting 50 in writing.

Third, the flow of ink is made much more uniform than in pens not protected by a guard, and with a fountain pen an average of 120 words per drop of ink can be regularly written.

Fourth, occasionally the first few letters written with a fountain pen that has not been used for a time, perhaps a day, are noticeably dark. 60 This is due to the fact that there has been some evaporation of moisture and a consequent concentration of the coloring matter at the point of the nib. This annoyance is lessened because the guard checks evaporation considerably.

Fifth, flooding and spilling of ink are diminished to a great extent.

Sixth, a pen of the fountain type according to this disclosure, may be left lying flat on the table or either point up or point down, and yet 70 it will start to write promptly and will remain quick-starting for a longer time.

In conclusion it is desired to state that another result of the use of some types of the guard is that cheaper material can be used in making 75

pen nibs. Persons usually pride themselves upon the bright and glittering appearance of a gold fountain pen nib, but out of economical considerations it is possible to virtually cover the nib as in Fig. 3, directing the owner's pride to the appearance of the guard which, if made of Celluloid, can be colored and will also shine. In this instance the nib can be made of stainless steel or some substance commonly used in 10 nib manufacture, and an expensive gold plating is not needed.

I claim:

1. A pen guard comprising a member to be fitted upon a nib, said member consisting of a 15 covering portion substantially covering one of the sides of the nib, said covering portion merging into laterally positioned and longitudinally extending marginal portions to grip the longitudinal margins of the nib and to lap over onto the 20 other side of the nib, said marginal portions having edges in confronting relationship contiguous to said other nib side.

2. A pen guard comprising a member to be fitted upon a nib, said member consisting of a 25 covering portion substantially covering one of the sides of the nib, said covering portion merging into laterally positioned and longitudinally extending marginal portions to grip the longitudinal margins of the nib, said marginal portions 30 narrowly overlapping the other side of the nib, being closely spaced from the longitudinal margins of the nib and having their edges in confronting relationship.

3. A fountain pen guard comprising a member

to be fitted upon a nib, said member including a relatively extensive nether wall to cover most of the feed bar of said pen, and marginal portions into which said nether wall merges, gripping the longitudinal margins of the nib and 5 extending slightly over the convex side thereof, the extremities of said portions appearing on top of said convex side being spaced from each other so that the guard is open on top at the front and rear.

4. A pen guard comprising a member to be fitted upon a nib, said member including means bridging the concave side of the nib to form a reservoir with said side, marginal portions into which said bridging means merge, said marginal 15 portions following parts of the nib margin leaving medial portions of the back of the nib exposed, and a wall receded from each of the guard member extremities connecting said marginal portions and being superimposed upon the nib back.

5. A pen guard comprising a member to be fitted upon a nib, said member consisting of a covering portion substantially covering one of the sides of the nib, said covering portion merging into laterally positioned and longitudinally 25 extending marginal portions to grip the longitudinal margins of the nib and to lap over the edges of said nib being closely spaced in from the nib margins, a wall springing from and connecting said marginal portions, and knurling on 30 the underside of said wall, facilitating the ink flow.

KENNETH W. MCPHERSON.
